UNITED STATES PATENT OFFICE.

ARTHUR FOUNTAIN, OF PAWHUSKA, OKLAHOMA.

RAILWAY-TIE.

1,212,930.

Specification of Letters Patent. Patented Jan. 16, 1917.

Application filed September 2, 1916. Serial No. 118,190.

To all whom it may concern:

Be it known that I, ARTHUR FOUNTAIN, a citizen of the United States, residing at Pawhuska, in the county of Osage and State 5 of Oklahoma, have invented a new and useful Railway-Tie, of which the following is a specification.

This invention has reference to railway ties, and its object is to provide a practically indestructible railway tie to replace 10 the customary wooden ties ordinarily employed in railroads.

In accordance with the present invention the body of the tie is made up of concrete 15 or vitrified clay, or the like, with a metal rail holding member introducible lengthwise through the assembled blocks forming the body of the tie, with means for retaining the rail holding member in place and 20 preventing spreading of the blocks, the arrangement being such that there is provided a certain amount of play or elasticity, preventing harmful effects due to expansion and contraction and conditions of travel.

25 The invention will be best understood from a consideration of the following detailed description, taken in connection with the accompanying drawings, forming part of this specification, with the further understanding that while the drawings show a practical 30 form of the invention, the latter is not confined to strict conformity with the showing of the drawings, but may be changed and modified so long as such changes come within 35 in the scope of the appended claims.

In the drawings, Figure 1 is a perspective view of a railway tie constructed in accordance with the present invention, with two track rails in place. Fig. 2 is an end view 40 of the tie with a rail in place and shown on a larger scale than Fig. 1. Fig. 3 is a vertical cross section through one of the blocks between the rails, the section traversing a pair of rail holding clips. Fig. 4 is a section on the line 4—4 of Fig. 2, with intermediate blocks of the tie omitted. Fig. 5 is a section on the line 5—5 of Fig. 4. Fig. 6 is a perspective view of one of the blocks making up the tie.

50 Referring to the drawings, there is shown a tie 1 formed of a series of blocks 2, each of which may be made of concrete or vitrified clay, or other suitable substance. The blocks are made relatively short in the di-

rection of the length of the tie, so that each 55 tie is made up of a considerable number of blocks, say six or seven or eight more or less, the blocks being placed end to end but not rigidly fastened together. Each block may be of substantially rectangular form 60 with that face constituting the bottom face in the installed position rounded or convex, as shown at 3, such shape being advantageous for tamping the tie.

Extending through each block 2 is a passage 4, the passage being located near what constitutes the top of the block in the installed position and open at both ends. The passage 4 is of general oval shape in cross section and opens by way of a slot 5 extending throughout the length of the block, the slot being bordered by overhanging shoulders 6 on opposite sides. While the passage 4 is shown as oval in shape, such particular shape is not obligatory, so long as the 75 passage has more or less the function of a dove-tail slot or passage.

Adapted to and extending lengthwise through the aligned slots 4 in a sufficient number of blocks 2 to constitute a tie there is a 80 similarly shaped tubular member 7, that is the tubular member 7 is of oval shape if the passage 4 be of such shape, or it is of other shape if the passage 4 be otherwise than oval. The tubular member 7 may be formed 85 of sheet steel of heavy gage. Along one side of the tube its walls are formed into parallel outstanding flanges 8 spaced apart far enough to receive an elongated plate or strip 9 of sufficient width to enter the interior 90 of the tube nearly to the inner wall of the tube opposite to that from which the flanges 8 project. The strip 9 is as long or approximately as long as the tube 7, and stops short of what constitutes the inner 95 lower wall of the tube by a distance of say, about one quarter inch. Those edges of the flanges 8 remote from the tube 7 are oppositely bent to form other flanges 10 together constituting a rail supporting table upon 100 which track rails 11 are placed and are held thereto in properly spaced relation by clips 12 held to the respective flanges 10 by bolts 13, so that the rails may be applied or removed at will without the necessity of the 105 use of spikes.

In order to hold the flanges 8 of the tubular member 7 together with the strip 9

intermediate thereof, both the flanges and the strip are traversed by bolts 14. At or near the ends of the strip 9 are brackets 15 on opposite sides of the strip riveted or otherwise secured thereto and fastened to the brackets at each end of the strip is a bar 16 of somewhat greater length than the width of the tube 7 and the passage 4 through which the tube extends.

When the parts are assembled, one or both of the bars 16 are removed and the blocks 2 are strung upon the tube 7 or the latter is moved through the passages 4 of the blocks after they have been placed in alignment and then the strips 16 are replaced, bolts 17 being employed to hold them to the brackets 15. After the ties have been properly located, then the rails are made fast to the supporting flanges 10 constituting the rail carrying table.

The tube 7 provides an elastic support for the rails taking up vibration, the passages 4 being of sufficient width and height to permit the slight give or flattening of the tube 7 under conditions of travel, especially on the passage of a train along the rails. Moreover, there is enough freedom of movement to compensate for expansion and contraction, and since the tie is made up of quite a large number of blocks, there is no liability of injury to the tie by breakage or splintering because of such expansion and contraction or from other causes. The tie structure is very readily assembled or dismantled and may be repaired at any time more readily than a wooden tie can be removed and replaced by a new tie in the ordinary railway construction.

Both steel and reinforced concrete or vitrified clay are substances not at all subject to decay and are strongly resistant to breakage. The longitudinally disposed central strip 9 extending through the steel tie member greatly stiffens this part and at the same time permits vibration without liability of injuring the curved part of the tie. Moreover, the clamping clips 12 may be made of spring steel, thus not only holding the rails firmly to the tie, but allowing for vibration without injury to the parts.

The tie as a whole is made up of a center or core piece in the form of a steel tube traversing a plurality of blocks of concrete, vitrified clay, or the like, with the tube provided with an elongated neck along one side extending through a slot in the block communicating with the passage therethrough, while the neck terminates in oppositely directed portions providing a table or support for the rails.

The composite tie is susceptible of quick and easy repair, for should one or more of the blocks become damaged the structure may be partially or wholly dismantled and the damaged blocks replaced even more

readily than a wooden tie can be removed and a new one installed.

What is claimed is:—

1. A railway tie comprising a metal core piece with a supporting portion for rails, and a body member composed of a plurality of blocks strung upon and held together by the core piece.

2. A railway tie comprising a metal core piece with a supporting portion for rails, and a body member composed of a plurality of blocks strung upon and held together by the core piece, the blocks having those faces constituting the lower face of the tie convexly rounded.

3. A railway tie comprising a series of aligned blocks with aligned passages therethrough opening at the tops of the blocks, and a tubular core piece extending lengthwise of the blocks and provided with means at the ends for holding the blocks together on the core piece and said core piece having rail supporting means at the top of the tie.

4. A railway tie consisting of a series of blocks of concrete or like material, each with a passage therethrough near what constitutes its upper face and opening to the exterior of the block through said upper face with the lower face of the block convexly rounded, and a metal core of tubular form of substantially the same length as the combined length of the assembled blocks and having a neck and a flange portion extending through and along the top of the blocks and constituting a supporting means for the rails.

5. A railway tie comprising a series of blocks with passages lengthwise therethrough and opening through the tops of the blocks and a rail supporting core piece of tubular form and extending lengthwise through the passages and alining the blocks and holding them together, said core piece having a neck portion extending lengthwise of the blocks and through the top of the blocks and there provided with oppositely directed flanges forming rail supports, the tubular member being provided with a longitudinally extended strip of a width to reach to a point close to the bottom of the interior of the tubular member to constitute a stiffening and abutting means.

6. A railway tie comprising a series of blocks with passages lengthwise therethrough and opening through the tops of the blocks and a rail supporting core piece of tubular form and extending lengthwise through the passages and alining the blocks and holding them together, said core piece having a neck portion extending lengthwise of the blocks and through the top of the blocks and there provided with oppositely directed flanges forming rail supports, the tubular member being provided with a longitudinally extended strip of a width to

reach to a point close to the bottom of the interior of the tubular member to constitute a stiffening and abutting means, said strip having removable bars at the ends for holding the blocks together when strung upon the tubular member.

7. A railway tie comprising a series of blocks of concrete or like material, each with a passage therethrough opening through the top of the block and a metallic member of tubular form on which the blocks are strung and constituting a holding means for the blocks, said tubular member having matching flanges along one edge rising through

the tops of the blocks and there oppositely spread to constitute supporting means for the rails, said tubular member having a longitudinal strip between the flanges and entering the tubular member to a point close to the inner bottom wall thereof.

In testimony, that I claim the foregoing as my own, I have hereto affixed my signature in the presence of two witnesses.

ARTHUR FOUNTAIN.
